UNITED STATES PATENT OFFICE.

WILLIAM C. STEVENS, OF MILWAUKEE, WISCONSIN, ASSIGNEE TO THE CUTLER-HAMMER MFG. CO., OF MILWAUKEE, WISCONSIN, A CORPORATION OF WISCONSIN.

MOTOR-CONTROLLER.

1,327,787.

Specification of Letters Patent. Patented Jan. 13, 1920.

Application filed September 6, 1917. Serial No. 189,937.

To all whom it may concern:

Be it known that I, WILLIAM C. STEVENS, a citizen of the United States, residing at Milwaukee, in the county of Milwaukee and State of Wisconsin, have invented new and useful Improvements in Motor-Controllers, of which the following is a full, clear, concise, and exact description, reference being and to the accompanying drawing, forming 10 a part of this specification.

This invention relates to improvements in motor controllers.

One of the objects of the invention is to provide a unitary electromagnetic controller having separate sets of contacts to respectively complete the motor circuit and effect acceleration of the motor but subject to delay in the performance of the latter function under given motor conditions.

Another object is to provide a controller of the character stated which may be governed from a single control station for starting, accelerating and stopping, and also for inching.

Another object is to provide a controller of the character stated having a plurality of control windings acting cumulatively in starting and controllable for opposed action thereof to effect quick disengagement 30 of the main switch contacts for stopping.

Other objects and advantages of the invention will hereinafter appear.

The accompanying drawing illustrates one embodiment of the invention and the same will now be described, it being understood that the invention is susceptible of embodiment in other forms falling within the scope of the appended claims.

In the drawing,

Figure 1 is a front elevation of the controller;

Fig. 2 is a side elevation thereof, partly in section, and

Fig. 3 is a diagrammatic view of one circuit arrangement for the controller.

The controller includes a main switch arm 1, carrying a contact 2 to engage a stationary contact 3, an accelerating switch arm 4 carrying a contact 5 to engage a stationary contact 6 and common electromagnetic control windings 7 and 8 for said switch arms, said windings being axially aligned and each of said switch arms constituting an armature therefor.

The windings 7 and 8 are mounted upon a core 9 and are provided with a U-shaped magnetic frame to which said core is attached, said frame being fixed to a suitable supporting panel 11 with its extensions 10^a and 10^b in a perpendicular relation to said panel.

The stationary contacts 3 and 6 are respectively carried by posts 12 and 13 projecting from the panel 11 and the switch arms 1 and 4 are carried by a common pivot pin 14 supported by and between ears 10^c and 10^d of the lower extension of the magnet frame (Fig. 1). The switch arm 4, which is L-shaped, is of magnetic material throughout its entire length and is provided at its lower end with a stop lug 4^a to abut a non-magnetic plate 15 on the under side of the magnet frame and at its upper end with a conical projection 4^b opposite the end of the core 9. Also, the switch arm 4 is provided with a non-magnetic screw 16 extending therethrough, axially of the conical projection, to engage the end face of the core 9 to provide an adjustable minimum air gap between said magnetic parts, said screw being provided with a lock nut 17. The switch arm 1, on the other hand, comprises a magnetic portion 1^a and a non-magnetic portion 1^b, the former being interposed between the arm 4 and the core 9 and recessed to receive the conical projection 4^b. Further, the arms 1 and 4 are respectively provided with springs 18 and 19 connecting the same to the panel 11 for bias of said arms away from the core 9, thus normally effecting engagement of the accelerating contacts 5 and 6 and disengagement of the main contacts 2 and 3.

Assuming energization of both windings 7 and 8 for cumulative action thereof, the same cause a magnetic flux to traverse both switch arms and such flux is divided between two circuits, one including the core 9 and extension 10^a of the magnet frame and the other including said core and extension 10^b of the magnet frame. Normally, however, there is an air gap between the arm 1 and extension 10^a of the magnet frame and between both arms and the core 9, while on the other hand, the arm 4 completes the other magnetic circuit save for the air gap between said arm and the core. Accordingly the greater part of the magnetic flux

initially traverses the circuit through the extension 10^b of the magnet frame, dividing between arms 1 and 4 for attraction of both arms to disengage contacts 5 and 6 and engage contacts 2 and 3. However, the non-magnetic portion 1^b of the arm 1 initially shunts the greater part of the magnetic flux traversing the extension 10^b of the magnet frame to the path through the arm 4 thereby enabling design and adjustment of the controller to insure against attraction of the arm 1 without attraction of the arm 4. The controller illustrated is so designed and adjusted and furthermore the arrangement is such, that joint operation of the two arms disengages contacts 5 and 6 prior to engagement of contacts 2 and 3. Thus the controller insures against engagement of the main switch contacts until after disengagement of the accelerating switch contacts.

Upon attraction of both arms, as described, the arm 1 engages the core 9 and extension 10^a of the magnet frame whereas the screw 16 maintains the arm 4 in a spaced relation with the core whereby the reluctance of the magnetic circuit through the extension 10^a is reduced below that of the magnetic circuit through the extension 10^b and arm 4. In consequence, part of the magnetic flux previously traversing the arm 4 is shunted through the arm 1 thereby rendering the arm 4 more sensitive to release upon a reduction in the attractive force of the two windings. In the controller illustrated the arm 4 is designed to be released upon a predetermined reduction in the current traversing the winding 7, for reengagement of the accelerating switch contacts while the main switch contacts are held closed subject to release upon deenergization of both windings or a change in the circuit connections thereof for opposed action.

Further, the controller includes auxiliary contacts 20 and 21, the former being carried by the main switch arm 1 and the latter by a post 22 projecting from the panel 11. These auxiliary contacts are normally disengaged and arranged to be engaged upon attraction of the main switch arm to engage main contacts 2 and 3.

Referring to Fig. 3, the same shows the controller as employed to control the continuity of circuit of a shunt motor 23 and to control a starting resistance R in series with the motor armature. Further it shows a control station comprising a normally closed push button 24 and a normally open push button 25, for the windings of said controller. The shunt field winding F of the motor is connected directly across the supply circuit L—L' while the controller serves to make and break the armature circuit.

The circuit arrangement is such that closure of push button switch 25 completes circuit from line L through the motor armature, by conductor 26 through winding 7, by conductor 27 through said push button switch, by conductor 28 to line L', and a circuit from line L by conductor 29 through winding 8 and a resistance r by conductors 30 and 31 to line L'. In a word, closure of this switch provides for connection of the winding 8 directly across the line through resistance r and for connection of the winding 7 across the line through the motor armature so that both windings are subjected to substantially the full line voltage for cumulative action thereof to attract both switch arms as above described. With these connections it is, of course, apparent that the winding 7 should be of sufficient resistance to prevent passage of an operating current through the motor armature, and it is to be assumed that the resistance of the winding 7 is of such value. When, however, the windings attract both switch arms, the arm 1 completes circuit for an operating current through the motor armature from line L through said armature and the resistance R and thence through said arm 1, contacts 2 and 3 and conductor 31 to line L'. Also, attraction of the switch arm 1 completes a circuit from the junction of conductors 27 and 30 through normally closed push button switch 24, by conductor 32, through auxiliary contacts 21 and 20 to arm 1 which in attracted position is connected to the right hand terminal of resistance R and to line L'. Thus assuming release of push button switch 25 the winding 8 remains connected across the supply circuit through resistance r while the winding 7 is shunted with the armature resistance R. Accordingly the winding 7 is subjected to a decrease in current as the armature accelerates upon the initial inrush of current, thereby tending to release switch arm 4 as above described. When switch arm 4 is released it short circuits resistance R and winding 7 by way of conductor 33 and contacts 5 and 6 for acceleration of the motor to full speed, but as will be apparent the arm 4 is held against release until the motor has accelerated to a predetermined degree upon the initial inrush of current. This provides for maintaining the resistance R in circuit for a given period, and as will be understood this period may be of any predetermined duration.

Further, the circuit arrangement is such that upon opening of push button switch 24 the winding 8 is disconnected from line L', while both windings 8 and 7 are included in a closed loop across the terminals of the motor armature for opposed action thereof, thus providing for quick release of the main switch arm to interrupt the circuit of the motor armature.

Still further the circuit arrangement is such that if switch 24 be held open, the

switch 26 may be employed for inching, the latter switch under such circumstances acting when released to interrupt the circuit of both controller windings for immediate 5 interruption of the armature circuit.

What I claim as new and desire to secure by Letters Patent is:

1. In combination, a motor and a unitary electromagnetic switch having separate sets of contacts to respectively complete the circuit of said motor and effect acceleration of said motor while its circuit is so completed and also having a winding subjected to control by said motor for timing the accelerating action of said accelerating contacts.
  2. In combination, a motor, a main switch, an accelerating switch operable with said main switch and also independently thereof and common electromagnetic control means for said switches to effect operation thereof sequentially, said electromagnetic means being associated with said motor for timing of the accelerating operation of the latter switch.
  3. In combination, a motor, a main switch, an accelerating switch operable with said main switch and also independently thereof and common electromagnetic control means for said switches including a winding in circuit with said motor, said electromagnetic means providing for operation of said switches sequentially and for arrest of the accelerating operation of the latter switch under given conditions in the motor circuit.
  4. In combination, a motor and a unitary electromagnetic switch having separate sets of contacts to respectively complete the circuit of said motor and effect acceleration of said motor while its circuit is so completed, said switch having a winding independent of the motor circuit and a winding in circuit with said motor.
  5. In combination, a motor, a series resistance, therefor, a main switch, an accelerating switch and electromagnetic means including a winding having a circuit to shunt the same with said resistance for effecting sequential operation of said switches subject to delay in the accelerating operation of the latter switch under given conditions in the motor circuit.
  6. In combination, a motor, a series resistance therefor, a main switch, an accelerating switch and common electromagnetic control means for said switches to effect sequential operation thereof and delayed accelerating operation of the latter switch under given conditions, said electromagnetic means including a winding independent of the circuit of said motor and a winding having connections to shunt the same with said resistance.
  7. In combination, a motor, a main switch, an accelerating switch biased to
- accelerating position and electromagnetic means to move the latter switch away from accelerating position and the former switch to circuit closing position and then release said latter switch but subject to delay under given motor conditions.
8. In combination, a motor, a series resistance therefor, an accelerating switch biased to shunt said resistance, a main switch, cumulative electromagnetic windings for operating said switches to interrupt the shunt around said resistance and complete the circuit of said motor and means for placing one of said windings in shunt with said resistance for release of said accelerating switch.
9. In combination, a motor, a series resistance therefor, an accelerating switch biased to shunt said resistance a main switch, cumulative electromagnetic windings for operating said switches to interrupt the shunt around said resistance and complete the circuit of said motor and means for placing one of said windings in shunt with said resistance for release of said accelerating switch and both of said windings in a shunt relation to the motor armature and in an opposed relation to one another for release of said main switch.
10. In combination, a motor, a series resistance therefor, an accelerating switch biased to shunt said resistance, electromagnetic control windings for said switches, normally engaged contacts and normally disengaged contacts for control of said windings, circuit connections whereby the latter contacts serve to establish energizing circuits for both windings to effect cumulative action thereof for opening of said accelerating switch and closure of said main switch, circuit connections whereby closure of said main switch establishes a maintaining circuit for one of said windings and circuit connections whereby the other of said windings is shunted with said resistance through said normally engaged contacts for subsequent release of said accelerating switch.
11. In combination, a motor, a series resistance therefor, an accelerating switch biased to shunt said resistance, electromagnetic control windings for said switches, normally engaged contacts and normally disengaged contacts for control of said windings, circuit connections whereby the latter contacts serve to establish energizing circuits for both windings to effect cumulative action thereof for opening of said accelerating switch and closure of said main switch, circuit connections whereby closure of said main switch establishes a maintaining circuit for one of said windings and circuit connections whereby the other of said windings is shunted with said resistance through said normally engaged contacts for

- subsequent release of said accelerating switch, said circuit connections also providing for connections of both of said windings across the armature of said motor to effect differential action thereof for release of said main switch.
12. In a motor controller, in combination, a main switch biased to open position, an accelerating switch biased to accelerating position and common electromagnetic operating means therefor controllable to move the latter switch away from accelerating position and the former switch to closed position and then release said accelerating switch while retaining said main switch in closed position.
13. In a motor controller, in combination, a main switch biased to open position, an accelerating switch biased to accelerating position and cumulative electromagnetic windings associated with said switches, said windings serving to move the latter switch away from accelerating position and the former switch to closed position and then release said accelerating switch while retaining said main switch in closed position.
14. In a motor controller, in combination, a main switch biased to open position, an accelerating switch biased to closed position and a common operating electromagnet therefor, each of said switches including a magnetic part providing an armature for said electromagnet and said electromagnet having a magnetic frame adapted upon attraction of the magnetic parts of both switches to divert from said accelerating switch a portion of its magnetic flux whereby said accelerating switch will be sensitive to release independently of said main switch.
- In witness whereof, I have hereunto subscribed my name.

WILLIAM C. STEVENS.
